US0D1049746S

(12) **United States Design Patent** (10) Patent No.: **US D1,049,746 S**
(45) Date of Patent: ** Nov. 5, 2024

(54) **FOOD PREPARATION DEVICE**

(71) Applicant: **SHARKNINJA OPERATING LLC**,
Needham, MA (US)

(72) Inventors: **Joshua D. Anthony**, North Billerica,
MA (US); **Dan Kestenbaum**,
Brookline, MA (US); **Gary V.
Palladino**, Roslindale, MA (US)

(73) Assignee: **SharkNinja Operating LLC**,
Needham, MA (US)

(**) Term: **15 Years**

(21) Appl. No.: **29/733,267**

(22) Filed: **Apr. 30, 2020**

Related U.S. Application Data

(63) Continuation of application No. 29/694,045, filed on
Jun. 6, 2019, now Pat. No. Des. 982,375.

Ferris, Glovsky and Popeo, P.C.

CLAIM

The ornamental design for a food preparation device, as shown and described.

DESCRIPTION

FIG. 1 is a perspective view of a food preparation device;
FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the figures illustrate parts of the food preparation device that form no part of the claimed design.

1 Claim, 7 Drawing Sheets
